CLAIM

The ornamental design for a combined car seat and stroller, as shown and described.

DESCRIPTION

FIG. 1 is a top plan view of a combined car seat and stroller showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a rear perspective view thereof; and,

FIG. 8 is a front perspective view thereof, with the wheels pivoted and the handle and foot rest extended for use as a stroller.

FIG. 1
